FOOD CANNING

Frederick C. Marx, Cincinnati, Ohio, assignor to
The Heekin Can Company, Norwood, Ohio, a
corporation of Ohio

Application October 9, 1941, Serial No. 414,386

3 Claims. (Cl. 99—182)

This invention relates to the mechanical canning of foods and is particularly concerned with means adapted for use in connection with can-heading machinery known as seamers, that is, machines in which each of a series of cans is carried into juxtaposition with a lid which is thereupon sealed by a suitable curling operation to the top of the can.

This invention concerns itself with means, operative during the passage of the filled cans to the lid-applying portion of the machine, during which interval, according to this invention, each can is operated upon, in the top portion, by a jet of steam under pressure whereby the air and gases are expelled from the can and the food therein whereby an increased vacuum within the can is provided.

An object of the invention is to provide steam injection means of this character which may be selectively controlled, both as to quantity of steam and pressure, in order to meet the requirements of various types of canning.

A further object of the invention is to retard the formation of the so-called "hydrogen swells" in cans stored away or stacked upon shelves as in stores.

Another object is the provision of means accomplishing the results described, which means are simple and efficient and may be applied to existing types of seamers.

These and other objects are attained by the means described herein and illustrated in the accompanying drawings in which:

Fig. 1 is an elevational view of a seamer to which the invention has been applied, parts being broken away.

Fig. 2 is a plan view of the table portion of the seamer with the invention in place thereon.

Fig. 3 is a cross-sectional view on the line 3—3 of Fig. 2.

As suggested above, one of the difficulties encountered in canned foods is the losses resulting from so-called "flippers," "springers" or "hydrogen swells" formed on cans as the result of the pressure of gases within, such "swells" rendering the cans of food unmarketable. These "swells" are especially noticeable in cans containing food having marked acid and color characteristics such as prunes, berries, carrots, the juices of grapes, prunes, etc. The present invention is particularly concerned with overcoming this difficulty by providing a greater vacuum in the cans by expelling the air and gases from the can and from the cellular structure of the food. This is accomplished by the steam jets referred

to which are repeatedly injected into the tops of the cans during passage of the latter to the seaming operation, the spent steam and expelled air and gases being carried off through suitable exhausts.

In greater detail and with reference to the drawings:

A seamer of the kind adapted to have the present invention applied thereto may comprise a base 5 supporting a standard 6 which in turn supports a table 7, and, spaced well above this, a shelf 8. The standard 6, in its upper portion, has a suitable vertical drive shaft mounted thereon (not shown) and from this drive shaft, through a suitable gear arrangement, a horizontal drive shaft 9 extends to a lateral portion of the machine where its power is transmitted through suitable chain and sprocket means, to other moving parts of the machine, as will be further referred to.

In accordance with well known practice, the filled but unlidded cans are adapted to be moved over the table 7 in spaced succession to the lid-applying operation. For thus moving the cans, there is provided a star wheel indicated at 10 (Fig. 3) mounted on the table 7, as at 11 (Fig. 2), and associated in drive relationship, by means which need not be detailed, with the horizontal drive shaft 9. The cans are introduced upon the table 7 at about the point indicated at 12 in Fig. 2. The star wheel rotates in the direction indicated by the arrows (Fig. 2) and each arm thereof carries one of the cans in a curvilinear path around to the opposite side of the table. Suitable guide means, including the outer guide 13 (Fig. 3) and the inner guide 52, maintain the cans in proper alignment during movement to the seaming operation. After being carried to the opposite side of the table by the star wheel, as mentioned, each can is then engaged by one of the fingers 14 attached to a sprocket chain 15, the upper reach 16 of which extends toward the rear of the seamer. Guide-rails 17 hold the cans in alignment during movement by the chain 15 and thereafter the cans are deposited, one at a time, upon a can lift 18 (Fig. 1). The operating assembly for the can lift 18 is housed on the adjacent side of the seamer, in the lower part thereof, as shown at 19. It will be understood that the can lift 18 is, in its lowered position, on the same level as the can bottoms at the time each can is deposited thereon. Immediately thereafter the can is lifted up to juxtaposition with a lid or cover which is thereupon applied to the can, in a well known manner, by the seam-

ing assembly positioned within the housing 20. The can lift 18 is immediately lowered and the seamed can is replaced by the succeeding can and the operation repeated, the seamed cans being ejected from the seamer as at 21. It may be remarked here that the movement of individual lids from the bottom of a stack 22 into alignment with the individual cans, is effected by a suitable lever (not shown) operated from a horizontal shaft 23 which, at its outer end, is provided with a sprocket 24 over which the chain 15 passes. It may be further pointed out that the vertical mounting shaft 11 of the star wheel has suitable connection with a horizontal shaft 25 (Fig. 1) extending to the side of the seamer and there provided with a sprocket 26 which is engaged by the chain 15. From thence the chain extends upwardly and passes over a sprocket 27 secured to a stud shaft 28.

The foregoing description will give sufficient mechanical background for the invention here under consideration. This comprises a curved plate 29 positioned above and corresponding with the pathway of the cans being carried by the star wheel. The plate 29 is formed along the center longitudinal line with an inverted channel 30 and along each edge thereof with enlarged segments 31 and 32 provided with interior passages 33 and 34. These passages are connected at intervals with the under face of the plate 29 by small ports 35.

The under face of the plate 29 and the channel 30 are covered by a contact plate 36 which at specified intervals is formed with perforations 37 communicating with the interior of channel 30.

The plate 29 is supported by the shelf 8 and table 7. For this purpose, one end of the plate 29 is secured as at 38 to the shelf. Further support is afforded the plate by means of an arm 39 secured to the shelf 8. Similar support arms 41 and 42 are secured as at 43 and 44 to the table 7. In Fig. 3 it will be seen that these arms are connected, as at 430, with suitable bosses 440 formed on the enlarged segments 31 and 32 of the plate 29. It will be seen in Fig. 2 that the outer end of the plate 29 is curled upwardly as at 45 to obviate interference with cans entering therebeneath.

A terminus plate 46 (Fig. 2) extending above the final straight portion of the can guideway has its end connected as at 47 with the end of the curved plate 29. A support arm 460 extends from shelf 8 to plate 46. Said terminus plate has a channel 48 which corresponds and connects with the central inverted channel 30 of the plate 29. The terminus plate 46 is also formed with an enlarged outer edge section 49 through which extends a passage 50 corresponding and connecting with the passage 33 of said plate 29. The passage 50, similarly, is provided with outlet ports 51 and the channel 48, opening on the underside of the plate 46, is covered by a plate member similar to the member 36 (Fig. 3) of the large curved plate 29 and provided with a similar perforation 53 (Fig. 2).

The sides of the can passage are formed by apron members 54 (Fig. 3) depending from and attached to the underside of the plate 29 so that the can passage is substantially enclosed.

Steam under pressure is projected into the central inverted channel 30 of the curved plate 29 and the corresponding channel 48 of the terminus plate 46, and the steam is injected into the top portion of each can during the passage

of the latter past each of the perforations 37 and 53 of the said plates. The means for accomplishing this result will now be described.

Figs. 1 and 2 show a closed steam box or chamber 55 suitably supported at the side of the seamer. This steam box is divided interiorly into an upper and lower compartment by a partition 56 and this partition is provided with a valve seat within which the head of a poppet valve 57 seats. Steam under pressure, from a suitable supply, is introduced into the lower compartment of the steam box through a conduit 58. The upper compartment of the steam box is connected by a tube 59 with the interior of the inverted channels 30 and 48 of the plates 29 and 46.

The lower end of the poppet valve 57 projects below the steam box and is there acted upon by a cam 60 (Fig. 1) secured to the outer end of the shaft 28 and so arranged as to actuate the valve 57. This actuation is synchronized with the cans traveling through the guideway in such fashion that steam is ejected through the perforations 37 and 53 just as the cans are passing beneath these perforations. It may be remarked in this connection, in Fig. 3, that the clearance between the top edge of the cans (one of which is indicated at 61) and the plate immediately thereabove is only sufficient to preclude the danger of interference with the movement of the cans through the guideway. The injection of steam into the tops of the cans from the perforations 37 and 53 is effected, therefore, with very little loss of pressure and contents of the cans. The injected steam, as has already been suggested, results in driving out air and gases from above or around the food in the can, which result is added to each time the can passes beneath one of the steam jets.

A final blast of steam is injected into each can immediately prior to the actual seaming operation, that is, just before the can becomes positioned upon the can lift 18. For this purpose the end of the inverted channel 48 (Fig. 2) of the plate 46 has connected thereto and communicating therewith a tube 62 which, at its opposite end as at 63 (Fig. 1), is directed toward the interior of the last can in the guideway for delivering the final blast of steam referred to. In Fig. 1 a can indicated at 64 is about to be carried beneath the ejection end 63 of the tube 62. It will further be seen that can 64 is traveling past suitable guide-rails 65 provided at the side of the can passage at this interval.

The spent steam and air ejected from the cans is carried off through the passages 33, 34 and 50 of the plates 29 and 46, being introduced into these passages through the small ports 35 and 51. The said passages 33 and 34 are connected by branch tube 66 (Fig. 1) with a main exhaust tube 67 and this latter is associated at its outer end with suitable negative pressure or suction means (not shown).

The plates 29 and 46 may be adjusted upwardly and downwardly to accommodate cans of different heights by adjustment means such as indicated at 68 and 69 (Fig. 3).

The cam 60 is operative on the poppet valve for an interval sufficient to effect the injection of steam into each can during the whole period of the latter's passage beneath the perforations 37 and 53. For varying the interval during which the steam jets are operative, the cam 60 may be replaced with others of selected sizes to procure the desired open interval of the poppet valve 57.

The application of the means of this invention to various types of seamers is a matter of simple mechanical expedients.

What is claimed is:

1. The combination with a seamer adapted to seal lids on filled cans of food, the seamer comprising a carrier for moving a series of cans to the sealing mechanism, of a steam injector positioned above the cans, means for actuating the injector to direct a blast of steam into the top of each can just prior to sealing thereof to drive out air and gases from the cans and provide an increased vacuum in the sealed cans, and means synchronized with the movement of the cans for actuating the steam blast during complete movement of the can therebeneath.

2. The combination with a seamer adapted to seal lids on filled cans of food, the seamer comprising a carrier for moving a series of cans to the sealing mechanism, of a covering plate positioned directly above the cans and formed with a passage communicating with the under surface of the plate, means for injecting steam through

said passage into the top of each can as the latter passes therebeneath for driving out air and gases from the cans and for providing thereby an increased vacuum in the sealed cans, and means synchronized with the movement of the cans for actuating the steam blast during complete movement of the can therebeneath.

3. The combination with a seamer adapted to seal lids on filled cans of food, the seamer comprising a carrier for moving a series of cans to the sealing mechanism, of a covering plate positioned directly above the cans and formed with a passage communicating with the under surface of the plate, means for injecting steam through said passage into the top of each can as the latter passes therebeneath for driving out air and gases from the cans and for providing thereby an increased vacuum in the sealed cans, and means synchronized with the movement of the cans whereby the steam jets are continued during total movement of each can therebeneath.

FREDERICK C. MARX.
